EXPANDING CHAIN FOR BRACELETS OR WRIST BAND FOR WATCHES

Alfred Pinson, Stamford, Conn., assignor to Apex Accessories Co., Inc., Greenwich, Conn.

Application January 22, 1952, Serial No. 267,625

5 Claims. (Cl. 59—79)

My invention relates to the type of lazy tong chains forming an alining series of units and has reference more particularly to the nesting of the unit parts in the retracted position of the chain.

Another object of the invention is to provide a predetermined angular relation between part of the unit and its relation to the longitudinal axis of the chain in the retracted and fully extended position.

A further object of the invention is to provide a chain of the type referred to in which the exposed surfaces of the elements lend themselves to a variety of shapes without any change in the construction of the chain elements proper.

Referring to the drawing forming part of this application:

Figure 1 is a plan of a fragment of the retracted chain, one unit of the chain being shown with the covers removed;

Figure 2 is a similar view showing a fragment of the chain fully extended with one section thereof having its covers removed to better illustrate the construction;

Figure 3 is a section on line 3—3, Figure 2.

Figure 4 is a section on line 4—4, Figure 1.

Figure 5 is a section on line 5—5 of the liner shown in Figure 7;

Figure 6 is a section on line 6—6 of the rocker bar shown in Figure 7; and

Figure 7 is a perspective view of the separate and spaced parts for a unit of the chain.

Referring to the drawing:

The chain units each comprise a liner 10 in the form of an eared circular washer, the two ears 11 of which liner are diametrically opposite and project from the convex edge of the liner and are co-planar with it. The liner 10 of each unit in the chain has the diameter passing through the ears thereof set at an angle of about 45° with the longitudinal axis of the chain in the retracted position.

Mounted pivotally between its ends on the inner face of the liner 10 is a rocker bar 12, the ends 13 of which overhang the convex edge of the liner. These ends are depressed so that the upper surface of said depressed ends 13 are substantially co-planar with the inner surface of the liner 10.

The pivot 14, which pins concentrically the rocker bar to the liner 10, permits angular displacement of at least 60° away from the ear to the same side of the longitudinal axis of the chain in the retracted position thereof. See Figure 1. In addition, the pinning of the rocker bar to the liner permits a certain amount of play between the contacting surfaces of said liner 10 and bar 12.

The rocker bar 12 and the liner 10 of the unit are engaged by a helical spring 15, positioned above the rocker bar 12 and concentric with the liner 10. The end 15' of the spring 15 is anchored to a hook 16 rising from the rocker bar 12, see Figures 6 and 7, while the other end 15" of said spring 15 is anchored to a lug 17, rising from the liner 10. Said lug makes an angle of about 45° with the nearest ear 11 of said liner 10. See Figures 1, 2, 3, 5, and 7.

The said spring 15 is so tensioned that it normally tends to bring the end 13 of the rocker bar 12 towards the ear 11 of the same unit with which the lug 17 makes a 45° angle. The angular movement of the rocker bar on the liner is not less than 60° and is limited between the retracted position of the unit by the engagement of

2

the end 13 of the rocker bar with the ear 11, and in the extended position by the engagement of the rocker bar 12 with the lug 17. See Figure 2.

An arcuated link 18 connects pivotally an ear 11 of the liner 10 to the proximate end 13 of the rocker bar of the adjacent unit on the same side of the longitudinal axis of the chain, so that the angular relation between the liner ears 11 and the rocker bar of each chain unit in retracted position is about 30° to each side of the chain's longitudinal axis. In the retracted position of the chain the ears 11 of the circular washer 10 are also on opposite sides of a line normal to the longitudinal axis of the washer that passes through the center of same, with each of said ears being adjacent to the proximate unit to which the ear is connected. The inner concave edge of the link 18 has a radius slightly greater than the radius of the convex edge of the liner 10. See Figure 1 (the exposed unit). Although the drawing shows the outer edge also arcuated, it does not have to be; it may take any form to suit the design to which the chain is to conform.

The tendency of the spring 15 is to draw the adjacent units and to move the links 18 to bring the concave edge thereof to be concentric with the circular part of the liner 10 of same unit due to engagement of the rocker bar ends with the ears. See Figure 1. When the chain is extended, as shown in Figure 2, the links 18 are moved between the adjacent units, and due to the predetermined angular displacements between the rocker bar and the liner of the units, the symmetry of the chain is maintained during the extension, as will be seen from Figure 2. In the fully extended position of the chain the liner and the rocker bar of each unit are at right angles and at 45° each to the longitudinal axis of the chain.

The liner 10 is provided with a cover 19; see Figures 3, 4, and 7. The skirt 21 of the cover is provided with diametrically opposite cut-outs 20 to permit the rocker bar to move angularly with reference to the liner. Suitable tongues 22 are provided on the lower edge of the skirt whereby the cover may be locked to the undersurface of the liner.

Each of the links is also provided with a cover 23; see Figures 1, 2, and 7. The skirt 24 of the cover 23 has suitable tongues 25 whereby it may be locked to the underside of the link 18 to provide a better support for the cover on the link. Lateral shoulders 26 are formed thereon to engage a recess 27 located to each side of the tongues 25.

It is to be noted that by limiting the angular movements of the liner and rocker bar by the engagement of the ears of the liner with the ends of the rocker bar in normal retracted position of the unit and that of the rocker bar with the lug 17 of the liner in fully extended position, there can be no strain on the skirt of the cover 19 for the liner by the angular movement of the rocker bar.

I claim:

1. An expanding chain formed of an alining series of units, each unit comprising a liner in the shape of a two-eared circular washer, the ears of which are diametrically opposite and disposed on opposite sides of the longitudinal axis of the chain from the retracted to the extended position thereof, a rocker bar mounted pivotally and concentrically with the liner and having its ends extending beyond the convex edge of the liner, said ears lying on opposite sides of the longitudinal axis of the chain and on opposite sides of a line normal to the longitudinal axis that passes through the center of said circular washer with each of said ears being adjacent to the proximate unit to which the ear is to be connected, a link to each side of the longitudinal axis of the chain having a concave inner edge of a radius greater than that of the convex edge of the liner and connected pivotally with one end to an ear of the liner and with the other end to the end of the rocker bar of an adjacent unit, a helical spring connected to the rocker bar and the liner to normally move the end of the rocker bar toward the ear of the liner lying to the same side of the longitudinal axis of the chain, said connection bringing the link into concentricity with the liner when

the unit is retracted by the spring to normal position, and a cover for said liner housing the spring and having means to permit a relative angular displacement between the liner and the rocker bar.

2. An expanding chain formed of an alining series of units, each unit comprising a liner in the shape of a two-eared circular washer, the ears of which are diametrically opposite co-planar with the liner, said ears lying on opposite sides of the longitudinal axis of the chain and on opposite sides of a line normal to the longitudinal axis that passes through the center of said circular washer with each of said ears being adjacent to the proximate unit to which the ear is to be connected, a rocker bar mounted pivotally and concentrically with the liner and having its end extending beyond the curved edge of the liner, said extending ends being depressed to bring the same into the plane of the liner, a link to each side of the longitudinal axis of the chain having a concave inner edge of a radius greater than that of the circular edge of the liner and connected pivotally with one end to an adjacent ear of the liner and with the other end to the proximate depressed end of the rocker bar of an adjacent unit, a helical spring above the rocker bar having its ends connected respectively to the bar and the liner, said spring normally tending to move the depressed ends of the rocker bar toward the ears of the liner lying to the same side of the longitudinal axis of the chain, the said connection bringing the inner concave edge of the arcuated link into concentricity with the circular edge of the liner when the unit is retracted by the spring to its normal position, and covers for said liner and links, said cover for the liner housing the spring and having means to permit a relative angular displacement between the liner and the rocker bar.

3. An expanding chain formed of an alining series of units, each unit comprising a liner in the shape of a two-eared circular washer, which ears are diametrically opposite, said ears lying on opposite sides of the longitudinal axis of the chain and on opposite sides of a line normal to the longitudinal axis that passes through the center of said circular washer with each of said ears being adjacent to the proximate unit to which the ear is to be connected a rocker bar mounted pivotally and concentrically with the liner and having its end portion extending beyond the circular edge of the liner, a helical spring connected to the bar and liner respectively and tensioned to normally maintain each end of the rocker bar against the ear of the liner, both end and ear lying to the same side of the longitudinal axis of the chain, the angular relation between the diametrically opposite ears and the rocker bar in the normal retracted position forming an angle of about 30°, a link to each side of the longitudinal axis of the chain having an arcuated inner edge of a radius greater than the circular edge of the liner and connected pivotally with one end to the ear of the liner and with the other end to the end of a proximate rocker bar of an adjacent unit, said connections of the link with the liner and the rocker bar being adapted to bring said links into concentricity with the liner in the retracted position of the chain, the lengths of the links to each side being such that the diameter passing through said ears of the liner forms an angle of about 45° with the longitudinal axis of the chain in the retracted position thereof, the rocker bar forming an angle of about 45° with the longitudinal axis of the

chain when the same is fully extended, and a cover for said liner housing the spring and having means for permitting the rocker bar to move angularly through an angle of more than 60° with reference to the liner.

5. An expanding chain formed of an alining series of units, each unit comprising a liner in the shape of a two-eared circular washer, which ears are diametrically opposite and co-planar with the liner said ears lying on opposite sides of the longitudinal axis of the chain and on opposite sides of a line normal to the longitudinal axis that passes through the center of said circular washer with each of said ears being adjacent to the proximate unit to which the ear is to be connected, a rocker bar mounted pivotally and concentrically with the liner and having its end portion extending beyond the curved part of the liner and depressed to lie in the plane of the liner, a helical spring mounted above the rocker bar engaging with its ends respectively the said bar and the liner, said spring being tensioned to normally maintain the rocker bar ends against the ears of the liner, both ear and end lying to the same side of the longitudinal axis of the chain, the angular relation between the diametrically opposite ears and the rocker bar in the normal retracted position of the chain forming an angle of about 30°, a link to each side of the longitudinal axis of the chain each having a concave inner edge of a radius greater than that of the convex edge of the liner, said link being connected pivotally with one end to the ear of the liner and with the other end to the proximate depressed end of a rocker bar of an adjacent unit, said connection of the links with the ears and the liner of the ends of the rocker bar being adapted to bring the said links into concentricity with the circular parts of the liner in the retracted position of the chain, the length of said links being such that the diameter passing through said ears of the liner forms an angle of about 45° with the longitudinal axis of the chain in the retracted position thereof, the rocker bar forming an angle of about 45° with the longitudinal axis of the chain when the same is fully extended, and covers for said liner and links, said cover for the liner housing the spring and having means for permitting the rocker bar to move angularly through an angle of more than 60° with reference to the liner.
35. An expanding chain as defined in claim 1 including; said liner having a lug near the circular edge thereof of rising above the inner surface to lie substantially in the longitudinal axis of the chain in the retracted normal position thereof and making an angle of about 45° with the diametrically opposite ears in said normal position of the chain, said lug being adapted to form an abutment for the rocker bar when the chain is fully extended.
